TELEPHONY

OF INTELLIGENCE

No. 863,852.

PATENTED AUG. 20, 1907.

I. KITSEE.

TRANSMISSION OF INTELLIGENCE BY ELECTRIC MEANS.

APPLICATION FILED FEB. 5, 1904.

UNITED STATES PATENT OFFICE.

ISIDOR KITSEE, OF PHILADELPHIA, PENNSYLVANIA.

TRANSMISSION OF INTELLIGENCE BY ELECTRIC MEANS.

No. 863,852.

Specification of Letters Patent.

Patented Aug. 20, 1907.

Application filed February 5, 1904. Serial No. 192,229.

To all whom it may concern:

Be it known that I, ISIDOR KITSEE, of the city and county of Philadelphia, State of Pennsylvania, have invented certain new and useful Improvements in the 5 Transmission of Intelligence by Electric Means, of which the following is a specification.

My invention relates to an improvement in the transmission of intelligence by electric means and has more special reference to transmission wherein mechanical 10 energy is converted at the sending station into electric energy and re-converted again into mechanical energy at the receiving station, such for instance as the transmission of speech with the aid of a telephonic sender and receiver.

15 In telephony, an all-metallic circuit is now almost universally employed in preference to the earth-return, for the reason that through the grounding of the line, the earth currents interfere too seriously with the transmission of speech. I have discovered that it is 20 possible, under certain circumstances, to communicate telephonically between two stations more or less remote from each other with only one metallic line and without using the earth as a return. The underlying principle of this my invention lies in the employment 25 of a local artificial line, preferably all-metallic, preferably joined together by condensers, which are preferably shunted with the aid of magnetic coils.

It is unnecessary for me to repeat here all the experiments made to obtain the most efficient arrangement 30 and it suffices to repeat only one of these experiments, in which I employed two stations, located in different rooms removed from each other by a hallway, and in which the line itself consisted to its greater part of iron wire. At each of the stations the artificial local circuit 35 consisted, besides the transmitting and receiving instruments, of resistances with the combined value of about 15,000 ohms, of an inductance of about 100 Henrys and of capacity devices with a combined value of about 8 micro-farads. The line itself joining these 40 two stations to each other consisted of about 5 miles of iron wire No. 28, and also of two coils, each of about 5000 ohms resistance and an inductance of about 44 Henrys, and of condensers with a capacity of about 6 micro-farads. The local circuits as well as the line 45 joining the same was carefully insulated from the ground and large porcelain insulators were used in every case and the test showed that no leakage to the ground whatsoever from the local circuit or line existed. The transmitting force at each station consisted 50 of three dry cells and the speech could be heard distinctly at both terminals.

To prove the theory that it is necessary to build up the local line to a value equal or higher than the line joining the two stations, the inductance was removed 55 from one of the local circuits with the result that the speech could not be heard at all: as this inductance con-

sisted of a series of individual coils, one of these coils was re-inserted in the line with the result that the voice could be heard but the words could not easily be distinguished. The gradual insertion of all of the series of 60 coils resulted in the gradual increase in the clearness of the transmitted speech, till with the insertion of the last of the series of coils, the former distinctness was again obtained. The removal and re-insertion of the 65 condensers effect the speech transmitted in the same manner, so also the removal and re-insertion of the ohmic resistance. After a full balance was obtained, the ohmic resistance and inductance of the line joining these two stations was increased about $\frac{1}{4}$ of its former 70 value and the clearness of the speech rapidly decreased with the insertion of these new devices.

In the drawings, Figure 1 is a diagrammatic view illustrating one form of the herein-described invention. Fig. 2 is a similar view illustrating the local and line connections to the condensers.

75

Referring now to the drawing, and in which similar letters indicate similar parts,—1 and 1^a are the two stations joined together by the line 2. At each of these stations A represents a battery, B a telephonic transmitter, C a magneto, c the bell for same, and G the ground for said bell. As usual, the magneto contacts through the lever with the line as long as the receiver is in its place, but breaks this contact as soon as the receiver is removed. In the drawing, this arrangement is shown by lever b and contact g¹. The battery A 85 connects with said lever as soon as through the removal of the receiver the lever contacts with the point b². In this circuit is inclosed the primary d of the device D; this primary is connected with one pole to the secondary d'; this secondary is connected to the artificial line. 90 As this device does not form a special part of this my invention, it is unnecessary to go more into detail of same, or to point out the reasons of the peculiar construction of same. The artificial line itself consists of the resistances h, capacity devices, shown in the drawing as condensers i, inductances, shown here as electro-magnetic coils j, and coreless coils k, which may perform the function of inductance as well as retarding coils. The terminals of each of these lines are connected to condensers and these condensers are shunted with the aid 95 of low resistance coils having a great magnetic flux through their soft iron cores. These coils are indicated by the letters N and N' and the condensers by the letters M and M', respectively. The condensers M and M' are double condensers, and form the subject of 100 a separate application filed June 26, 1897, Ser. No. 642,495. The receiving device consists of the device F in conjunction with the receiver E. The device F embraces the coil f¹ in which is inserted the coil f joined with one terminal to one terminal of the first 110 named coil. In reality, this arrangement may be likened to an inductorium and as the special features

of same do not form part of this my invention, I do not describe them in particular and only state that the receiver E has to be in electrical connection with the coil f which, if the similarity of the inductorium is carried out, may represent the primary of same.

To conveniently adjust the local circuits so as to conform with the line-proper, I have provided each of the devices with the plug m in electrical contact with that part of the line to which its particular device pertains.

10 With the aid of this device, it is an easy matter to plug in or out one or more of the resistances, capacities or inductances, as it is self-evident that the line supposedly running from Philadelphia to Chicago requires a balancing local of greater value than a line running from Philadelphia to New York. The parts of the local circuit as well as the line-proper should be well insulated and the grounding of any part, with the exception of the grounding of the bell and magneto when no speech is transmitted, should positively be avoided.

15 The *modus operandi* as far as the operation is concerned, is the same as in the usual individual long distance telephony: The person calling rings-up the second station, awaits an answer, and then removes the receiver from the hook. The second station, answering, has also to remove his receiver. This removing of both receivers breaks entirely the connection of the line with the ground and if, as said above, all parts are well insulated, a one-line circuit without a ground is established.

20 These, in broad outlines, are the main features of my invention and I have illustrated here an individual line

because to persons versed in the art this will readily give a clear conception of the whole arrangement, but it is obvious that this arrangement may also be used in connection with a central station.

35

Having now described my invention, what I claim as new and desire to secure by Letters Patent is:—

1. An electric line of transmission, consisting of two local circuits more or less remote from each other and a line joining said local circuits, each of said local circuits having a value at least equal to the value of the line proper.

2. As a means to electrically communicate between two points more or less remote from each other, over a one-legged line without earth connection, artificial local circuits at each of said points, each of said local circuits having a value at least equal to the value of the line-proper, the terminals of the line-proper connected to said local circuits.

3. In combination with a line of electric transmission, two local circuits possessing ohmic resistance, capacity and inductance, of means to vary said values, said local circuits connected to said line of transmission through condensing devices.

4. Means to communicate electrically between two points more or less remote from each other, said means embracing telephonic transmitters including in their circuits sources of energy, a local circuit at each point embracing devices to give said circuits an ohmic value, a capacity and inductance, telephonic receivers and a conductor connecting both of said local circuits to each other.

In testimony whereof, I hereby sign my name in the presence of two subscribing witnesses, this third day of February, A. D. 1904.

ISIDOR KITSEE.
